(57) **CLAIM**

The ornamental design for a coolant containing device to treat internal hemorrhoids and external hemorrhoids, as shown and described.

DESCRIPTION

FIG. 1 is a side perspective view of the present invention; FIG. 2 is a reduced bottom and side perspective view of the present invention;

FIG. 3 is a reduced bottom and side perspective view of the present invention;

FIG. 4 is a reduced top view of FIG. 1; and,
FIG. 5 is a reduced bottom view of FIG. 1.

1 Claim, 5 Drawing Sheets
